RELAY SYSTEM

Samuel E. McFarland, Los Angeles, Calif.

Application June 12, 1939, Serial No. 278,687

3 Claims. (Cl. 200—106)

This invention relates to railway signalling apparatus and relates more particularly to the relay systems and relays employed for the control of such signalling apparatus. A general object of this invention is to provide simple, practical and dependable line relays and relay systems for the control of intersection signals, etc.

This application is a division in part of my co-pending application, Serial No. 203,538, entitled Track signal control system which has matured into Patent No. 2,186,201, of January 9, 1940.

In control systems for governing railway intersection signals, etc. it is now the general practice to employ two line relays for the control of the signals and an interlocking relay governed by the line relays to prevent signal operation following the passage of the car or train over the intersection. The interlocking relay of an installation of this type is complicated and quite expensive and materially increases the cost of the installation.

Another object of this invention is to provide a system of relays for the control of intersection signals, etc. that does not require the use of an interlocking relay and, therefore, is much less expensive than the systems now in general use, is simpler to install, and is less liable to failure.

Another object of this invention is to provide a relay system for controlling intersection signals, etc. that embodies two line relays provided with simple, inexpensive interlocking means directly controlling their movable elements and serving to perform all of the functions of the complicated and expensive special interlocking relays heretofore required in such systems.

Another object of this invention is to provide a line relay for incorporation in an intersection signal control system that embodies a simple, yet dependable, latch means electrically set or operated as by the closing of contacts in a related line relay and mechanically restored or reset upon the resumption of normal current flow in the relay.

Another object of this invention is to provide an effective and thoroughly dependable latch means for attachment to or incorporation in a standard or typical A. C. line relay of the vane type, or the motor type, that is controllable by a related line relay, or the like, to prevent falling or shifting of the movable element until current is restored to the normal holding coils, whereupon it automatically releases to allow subsequent normal operation of the relay.

A further object of this invention is to provide a latch means of the character mentioned that

may be easily applied to or embodied in a typical line A. C. relay of either the motor type or the vane type without altering or modifying the general relay structure.

5 The various objects and features of my invention will be fully understood from the following detailed description of typical preferred forms and applications of my invention, throughout which description reference is made to the accompanying drawing, in which:

10 Fig. 1 is a diagrammatic view of the relay system of the present invention, employing motor type line relays. Fig. 2 is a fragmentary vertical detailed sectional view of one of the line relays of the system illustrated in Fig. 1 showing the latch means in its released or normal condition. Fig. 15 3 is a fragmentary vertical detailed sectional view taken as indicated by line 3—3 on Fig. 2. Fig. 4 is an enlarged side elevation of the latch means removed from the relay. Fig. 5 is a fragmentary vertical detailed sectional view of a vane type line relay provided with the latch means of the present invention, and Fig. 6 is an enlarged end view of the latch means being a view taken as indicated by line 6—6 on Fig. 5.

20 The relay system of the present invention may utilize typical A. C. line relays of any standard construction. In Figs. 1 to 4, inclusive, I have shown a system embodying typical motor type relays while in Figs. 5 and 6 I have illustrated one manner in which a standard vane type line relay may be provided with the improved latch means of the invention.

25 The relay system of the invention illustrated in Figs. 1 to 4, inclusive, may be said to comprise, generally, two line relays R responsive to conditions in rail circuits at opposite sides of an intersection and operable to control crossing signals, or the like (not shown), and latch means 30 for each relay R comprising a latch 10 and an electromagnetic actuating means 11 for the latch 10.

35 The relays R include suitable housings or cases 12 and pairs of vertically spaced substantially 40 horizontal supports 13 secured in the cases. The upper support 13 of each relay R carries downwardly facing contacts 14. The contacts 14 are usually termed the front contacts and are adapted to be connected in signal circuits or other circuits to be controlled by the relays R. In the case illustrated it may be assumed that one contact 14 of each relay R is connected in a circuit 45 energizing a green light or a go signal. The other front contacts 14 may be connected in circuits governing other signals or devices although 50

in the simple installation illustrated they are not connected in circuits but are idle. The conductors of the circuits 16 are connected with suitable binding posts 15 on the cases 12 and short wires connect the contacts 14 with the posts 15. The lower supports 13 of the relays R carry upwardly projecting contacts 17 and 18. The contacts 17 and 18 are usually termed the back contacts. One or more back contacts may be connected in signal control circuits. In the typical case illustrated it will be assumed that the contacts 17 are connected in circuits 19 for controlling a red signal or a stop signal at the intersection. The back contacts 18 are connected in the circuits for the control of the electro-magnetic means 11 as will be subsequently described. It is to be understood that each relay R may include as many front and back contacts as the installation may require.

The relays R further include flexible spring arms 20 carrying contactors 21 for cooperating with their respective contacts 14, 17 and 18. There is a contactor 21 for cooperating with each front contact 14 when the arms 20 are in their up positions and a contactor 21 for cooperating with each back contact 17 and 18 when the arms 20 are in their down positions. The contactors 21 are in the nature of branches or forks on the outer ends of the spring arms 20. The arms 20 are secured to common carriers 22 by suitable insulating means and the carriers 22 have trunnions or pins 23 turnable in bearings 24 secured in the cases 12. The arms 20 mounted in this manner are adapted to move simultaneously upon pivoting of their carriers 22. The power source lines P of the circuits 16 and 19 are connected with posts 9 on the cases 12 and flexible wires connect the arms 20 with the posts 9.

The means for shifting or operating the arms 20 comprise A. C. motors 25 in the cases 12. The motors 25 each include pairs of windings 26 and 27 and each motor turns a shaft 28. The windings 26 may receive current from a suitable A. C. power circuit 29 while the windings 27 may be connected in circuits 30 which are coupled with the rails to be shunted out upon the passage of a car or train over predetermined zones of the track. A pinion 31 is fixed to each motor shaft 28 and meshes with a sector gear 32. The gears 32 are fixed to shafts 33 carried by suitable brackets 34 in the cases 12. Cranks 35 are fixed to the gear shafts 33 and links 36 are pivotally connected with the cranks 35. A crank or arm 37 is provided on each carrier 22 and the links 36 are pivotally connected with the upper ends of the arms 37. It will be seen that movement or swinging of the gears 32 serves to move the arms 20 between their up and down positions. Stops 38 are secured in the cases 12 and serve to limit movement of the gears 32. Under normal conditions the windings 26 and 27 of both relays R are energized to hold the gears 32 in the up positions where the contactors 21 are in cooperation with the front contacts 14 to complete the circuits 16. Upon de-energization of a winding 27 of a relay R the gear 32 of that relay falls or swings down by gravity to move the contactors 21 out of engagement with the upper or front contacts 14 and to bring the lower contactors 21 into engagement with the contacts 17 and 18. This opens the circuit 16 and closes the circuit 19 so that the signal at the intersection is changed from green to red or from go to stop. The relays R thus far described are typical or standard.

The latch means are important features of the

invention. There is a latch means associated with each relay R and the latch means of one relay R is under the control of the other relay R thus providing an interconnection between the two relays. Upon de-energization of the winding 27 of one relay R and the resultant falling of its gear 32, the latch means of the other relay R is immediately made operative to prevent falling of its gear 32 so that the second relay is incapable of causing operation of the signal governed by its circuit 19 when the train or car leaves the intersection and the rail zone governing the first relay. The two latch means may be identical and are characterized by the fact that they may be easily embodied in standard line relays without reconstruction or alteration of the relays. Each of the latch means may include a base 40 adapted to be suitably secured in the relay case 12. Each base 40 has spaced upstanding posts 41 and 42.

The latches 10 of the latch means are elongate members supported on their respective bases 40 to project upwardly in adjacent relation to one of the moving elements of the related relay R. In the construction illustrated the lower ends of the latches 10 are pivotally supported by pivot pins 43 carried by suitable bearings 44 on the bases 40. The latches 10 normally rest or recline against stops. The latch supporting stops are preferably adjustable and may take the form of set screws 45 threaded through openings in the posts 41. In the typical form of the invention illustrated the latches 10 project upwardly to be in adjacent relation to the sides of the gears 32. The upper ends of the latches 10 are curved having curved faces 46 that continue downwardly along what may be termed the inner edges of the latches. An upwardly facing notch 47 occurs at the lower end of each curved face 46. The faces 46 serve as cams, as will be later described.

Projections are provided on moving elements of the relays R to cooperate with the latches 10. Where the latches 10 are located as described above, the projections may be in the nature of pins 48 projecting laterally from the lower portions of the gears 32. The latch engaging pins 48 are preferably adjacent the peripheries of the gears 32. The parts are related so that the latches 10 are out of the paths of the pins 48 when the latches rest against the stops 45. The latches 10 do not normally stop or interfere with the downward movement of the gears 32 when the windings 27 are de-energized.

The electro-magnetic actuating means 11 are operable to move their respective latches 10 to positions where the latches limit or prevent downward movement of the gears 32 and, therefore, prevent disengagement of the contactors 21 from the front contacts 14. Each electro-magnetic means 11 comprises a solenoid coil 49 supported on a post 42 and operable when energized to attract its related latch 10 to bring the latch to a position where the pin 43 of the adjacent gear 32 is receivable in the latch notch 47. The latches 10 may have thickened portions or blocks 50 opposing the cores of the coils 49. The coils 49 are operable when actuated to swing the latches 10 from their retracted positions to their active positions where they are engageable by the pins 43 to stop or limit down swinging of the respective gears 32. Electrical conductors or leads 51 connect the solenoid coil 49 of one relay R with a back contact 18 and the related arm 29 of the other relay R so that the solenoid coil 49 of one relay is energized when the gear 32 of the

other relay drops. Fig. 1 of the drawing clearly illustrates the manner in which the leads 51 connect the latch actuating coils 49 with the contacts 18 and the arms 20. As the gears 32 are normally held in their up positions the contactors 21 are normally out of engagement with the back contacts 18 and the solenoid coils 49 are normally de-energized so that the latches 10 rest against their stops 45 where they are out of the paths of the pins 48. The coil energizing leads 51 may be connected in suitable power leads 52.

In the operation of the relay system illustrated in Figs. 1 to 4, inclusive, the parts are normally in the positions illustrated in the drawing where the contactors 21 engage the front contacts 14 to complete the circuits 16. When a car or train approaches the intersection or enters the rail zone with which the circuit 30 of one relay R is coupled the winding 27 of that relay is shunted out allowing the gear 32 to fall by gravity. As the latches 10 are normally in the retracted positions the gear 32 is free to fall to its down position so that the contactors 21 are moved out of engagement with the front contacts 14 and come into engagement with the back contacts 17 and 18. Thus the signal circuit 19 is closed simultaneously with opening of the signal circuit 16 and the leads 51 connected with the contact 18 and its related arm 20 are electrically connected to complete a circuit to the solenoid coil 49 of the other relay R. Upon energization of this solenoid coil 49 the adjacent latch 10 is moved to the position where its notch 47 is in the path of the pin 48 on the adjacent gear 32.

The parts remain in the positions just described until the train or car has passed the intersection and enters the rail zone governing the circuit 30 and the winding 27 of the second or energized relay R. When this occurs the circuit 30 of this relay is shunted out and the gear 32 of the relay is released to drop. However, as the latch 10 of that relay is held in its active position by the coil 49 the gear 32 falls or moves but a very short distance when its pin 48 cooperates with the latch notch 47. The engagement of the pin 48 in the notch 47 of course stops or prevents falling of the gear 32 and the slight initial movement of the gear 32 is insufficient to move the contactors 21 out of engagement with the front contacts 14. Accordingly, the signal circuit 16 of the second relay is unaffected and remains completed while the signal circuit 19 of said second relay remains open. The engagement of the pin 48 in the notch 47 is such that it prevents the return of the latch 10 to its retracted position when the solenoid coil 49 is de-energized. Because of this relation the de-energization of the coil 49 resulting from the return of the gear 32 of the first relay does not release the actuated latch 10. The pin 48 remains in engagement with the notch 47 as long as the car or train remains in the rail zone governing the circuit 30 of the second relay R. When the car or train leaves the rail zone governing the second relay R the winding 27 of the relay is re-energized and the gear 32 is restored to its original up position. However, as the latch 10 has prevented the gear 32 from moving downwardly an appreciable distance the gear 32 is moved upwardly but a slight distance. The short upward movement of the gear 32 results in engagement of the pin 48 with the curved surface 46 and this engagement swings the latch 10 to its retracted position where it rests against the stop 45. Thus the latch 10 is restored to its normal retracted posi-

tion upon the resumption of current flow through the winding 27 of the second relay. The operations described above are repeated upon the movement of the car or train on the track in either direction.

Figs. 5 and 6 illustrate the invention embodied in or applied to a line relay R' of the vane type. The relay R' comprises the case 12^a, spaced rows of contacts 60 and 61 mounted on a wall of the case 12^a and a pivoted carrier 62 supporting contactors 63 for engagement with the contacts 60 and 61. The contacts 60 and 61 correspond in function to the front and back contacts 14 and 17-18, respectively, of the relays R described above. It is to be understood that there may be as many contacts 60 and 61 as required. The contactors 63 are, of course, suitably insulated from their carrier 62. The contactors 63 are such that they move from positions where they cooperate with the front contacts 60 to positions where they cooperate with the back contacts 61 when the carrier 62 pivots. The means for moving the carrier 62 comprises a vane 64 fixed to a shaft 65 which in turn is supported on a suitable post 66^a in the case 12^a. The vane 64 is normally held in its up position by the fields of coils 66 corresponding in function to the windings 26 and 27 of the motor type relays R. Upon de-energization of a winding 66 receiving its current from a rail circuit the vane 64 falls or pivots downwardly by gravity. Stops 67 are mounted in the case 12^a and are engageable by arms 68 on the opposite ends of the vane 64 to limit the movement of the vane. A crank 69 is fixed to the vane shaft 65 and a link 70 is pivotally secured to the crank. A second link 71 is secured to the carrier 62 and is pivotally connected with the outer end of the first link 70. When the vane 64 is in its normal up position illustrated in Fig. 5 the contactors 63 are in engagement with the front contacts 60. Upon de-energization of a holding coil 66, the vane 64 falls by gravity and the carrier 62 is pivoted to the position where the contactors 63 are in engagement with the contacts 61. The relay R' thus far described is of standard or typical construction.

The latch means of the invention may be arranged in the case 12^a to cooperate with any moving element of the relay R' to prevent reversal of the contactors 63 upon deenergization of the rail circuit controlled holding coil 66. The latch means employed in the relay R' may be identical with the latch means described above. In the typical application illustrated the latch means is arranged to cooperate with a part on the vane 64. The base 40 of the latch means may be secured to the bottom of the case 12^a in a position where the latch 10 is engaged by a pin 48^a projecting from the lower arm 68 of the vane 64. The latch 10 is positioned so that it is out of the path of the pin 48^a when resting against its stop 45. Upon energization of the solenoid coil 49 the latch 10 is moved to a position where the pin 48^a is receivable in the notch 47. The engagement of the pin 48^a in the notch 47 stops or limits the downward movement of the vane 64 and prevents the contactors 63 from moving out of engagement with the front contacts 60 when the holding coil 66 is de-energized. Two relays R' provided with the improved latch means of the present invention may be interconnected in the same manner as the relays R described above.

It is to be noted that the latch means provided

by the present invention may be easily and inexpensively embodied in the standard line relays without reconstructing or modifying the general relay structure. The latch means make it unnecessary to employ the usual interconnecting relays and their use greatly reduces the cost of installation and servicing. The latch means are extremely simple and are such that they may be mounted to cooperate with or control any selected moving element of a relay.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. A control for a line relay having spaced sets of contacts, a movable contactor element for engaging said contacts, a motor, and a gear operated by the motor in one direction to engage the contactor with one set of contacts and movable by gravity in the other direction to engage the contactor with the other set of contacts, the control comprising a pin on the gear, a pivoted latch normally held by gravity in a position clear of the arcuate path of the pin, and electro-magnetic means operable to move the latch to a position where it is engageable by the pin to limit falling of the gear when the motor is de-energized to maintain the contacts engaged, the latch having a notch for receiving the pin to limit falling of the element and cooperable with the pin to prevent return of the latch to the normal retracted position prior to reenergization of the motor.

2. Apparatus of the character described comprising a movable relay element, contacts controlled by the element, power means for holding the element in the position where the contacts are engaged, the element being adapted to fall

upon deenergization of the power means, and releasable means for latching the element in the position where the contacts are engaged in the event of deenergization of the power means comprising a part on the element, a latch normally out of the path of said part and movable into a position to be engaged by said part to prevent falling of the element to a sufficient extent to disengage the contacts, and electro-magnetic means for moving the latch into said position, the latch presenting a surface engageable by said part to limit falling of the element and cooperable with said part to prevent return of the latch to its normal position in the event of deenergization of the electro-magnetic means prior to reenergization of the power means.

3. Apparatus of the character described comprising a movable relay element, contacts controlled by the element, power means for holding the element in the position where the contacts are engaged, the element being adapted to fall upon deenergization of the power means, and releasable means for latching the element in the position where the contacts are engaged in the event of deenergization of the power means comprising a part on the element, a latch normally out of the path of said part and movable into a position to be engaged by said part to prevent falling of the element to a sufficient extent to disengage the contacts, and electro-magnetic means for moving the latch into said position, the latch presenting a first surface engageable by said part to limit falling of the element and cooperable with said part to prevent return of the latch to its normal position in the event of deenergization of the electro-magnetic means prior to reenergization of the power means, and a second surface engageable by said part upon upward movement of the element subsequent to deenergization of the power means to return the latch to its normal retracted position.

SAMUEL E. McFARLAND.
